DESIGN FOR A DISPLAY BOX FOR STATIONERY

Irving Wansker, New York, N. Y.

Application February 1, 1945, Serial No. 117,719

Term of patent 14 years

(Cl. D80—5)

To all whom it may concern:

Be it known that I, Irving Wansker, a citizen of the United States of America, residing in New York city, county of New York, and State of New York, have invented a new, original, and ornamental Design for a Display Box for Stationery, of which the following is a specification, reference being had to the accompanying drawing, forming part thereof,

The figure on the drawing is a perspective view of a display box for stationery showing my new design. The opposite side is substantially plain.

I claim:

The ornamental design for a display box for stationery, substantially as shown and described.

IRVING WANSKER.
